DESIGN FOR A WATER BOTTLE OR SIMILAR ARTICLE

Mary Marjorie Smith and Earla M. Roberts, Lancaster, Pa., assignors to Armstrong Cork Company, Lancaster, Pa., a corporation of Pennsylvania

Application May 27, 1939, Serial No. 85,236

Term of patent 14 years

To all whom it may concern:

Be it known that we, Mary Marjorie Smith and Earla M. Roberts, citizens of the United States, residing in Lancaster, county of Lancaster and Commonwealth of Pennsylvania, have invented a new, original, and ornamental Design for Water Bottles or Similar Articles, of which the following is a specification, reference being had to the accompanying drawing, forming a part thereof, in which bottle or similar article embodying our new design.

The opposite side of the water bottle from that shown in the drawing has substantially the same appearance as the side illustrated.

We claim:

The ornamental design for a water bottle or similar article, substantially as shown and described.

MARY MARJORIE SMITH.
EARLA M. ROBERTS.
